VERTICAL CARD INDEX CABINET

Birger Aagaard, Trondhjem, Norway

Application August 5, 1933, Serial No. 683,885

5 Claims. (Cl. 129—16)

This invention relates to improvements in vertical card index cabinets and embodies improvements upon the devices described and claimed in my United States Patent No. 1,926,023, dated Sept. 12, 1933, which embodies mechanism whereby a horizontally-disposed row of cards are raised and lowered above a card dropping element to enable a separation or break in the row or body of cards by a dropping of a portion of said row over and below the top edge of said dropping element with a consequent exposure of a portion of the face of a card or cards at said break or separation and to cause another portion of said cards to be supported by said dropping element in such a manner that by a pulling movement exerted manually on the handle of the drawer, the cards will move along the card-supporting portion of the dropping element until they reach the edge of said element, over which they drop one by one to a lower plane, the addresses of successive cards becoming visible during the dropping operation so that the card or cards wanted may be found without touching the cards with the hands.

One of the objects of my present invention is to provide mechanism for the control of the movement of the drawer and thus to control mechanically the speed and positiveness with which the cards are dropped over the dropping element.

Another object of my present invention is to avoid a packing of the cards during the forward movement of the drawer, to retain the same in their normal loose and unpacked relationship, thus facilitating the dropping operation, and also to provide for a substantially frictionless movement of the supported cards to the dropping edge during movement of the drawer for that purpose, and to this end I interpose between the card-supporting portion of the dropping element and the bottom of the cards, a belt movable with the drawer, and preferably formed of a suitable fabric which will engage the bottom of the cards to hold the same in their normal unpacked relationship during movement thereof along the supporting portion of the dropping element to the dropping edge.

Another object of this invention is to improve the constructional features of devices of the character specified by providing a card-containing drawer which will be readily separable or demountable from the cabinet and also providing a carriage therefor having spring-supporting mechanism adapted to permit the facile raising and lowering of the row or body of cards to procure the break in the row and dropping herein-

above specified. Thus, instead of mounting in a horizontal slideable drawer a vertically-movable card-carrier as in my said former application, the cards are mounted in a separate card-containing drawer, and this card-drawer itself is mounted in a carriage member to provide for horizontal sliding movement while the movement vertically from a plane in which the cards are above the dropping element to a lower plane is provided by a vertical movement of the drawer in relation to the carriage member, the cards, when the drawer is in its upper position, being supported at the bottom edge of the drawer while when the drawer is in its lower position the cards will be supported by the supporting portion of the dropping element with the belt above specified extending between the bottom of the cards and said supporting portion so that when in said lower position, the drawer is pulled, a portion of the cards which are held elevated by the dropping member will be successively dropped over the edge of the dropping element with a consequent exposure of a portion of the face of a card or cards whereby the addresses of each of such cards will become visible during the dropping operation and the card or cards wanted may be found quickly and surely without touching the cards with the hands.

In this preferred embodiment of my invention, the card drawer is therefore mounted in such a manner that it may be alternately moved vertically in relation to the casing from a plane above the top of the dropping element to a lower plane, while at the same time said drawer is movable with the carriage therefor horizontally in said casing. To effect these combinations in a practical manner, the card drawer is nested in a frame member which acts as a connection element between the casing and the card drawer, this frame member being slideable horizontally in said casing either by means of suspension slides or otherwise and thereby acting as a carriage for the card drawer to move the same out of the casing and back, said card drawer being mounted in such a manner in said frame as to enable the card drawer to be vertically moved in said frame and independently of the joint horizontal movement of said carriage frame member and said card drawer.

With these and other objects in view, the invention comprises the combination of members and arrangement of parts so combined as to coact and co-operate with each other in the performance of the functions and the accomplishment of the results herein contemplated, and

comprises in one of its adaptions the species or preferred form illustrated in the accompanying drawings, in which:—

Fig. 1 is a longitudinal vertical section of an index cabinet embodying my invention, showing the drawer partly opened and cards being dropped to expose a series of successive addresses; taken along the line 1—1 of Fig. 3.

Fig. 2 is a section similar to Fig. 1 showing the drawer in closed position; and taken along the line 2—2 of Fig. 4.

Fig. 3 is a transverse section on the line 3—3 of Fig. 1; Fig. 3a is a detailed section on the line 3a—3a of Fig. 3.

Fig. 4 is a transverse section on the line 4—4 of Fig. 2.

Fig. 5 is a detail view of latching mechanism for holding the drawer in its lowered position; taken along the line 5—5 of Fig. 1.

Fig. 5a is a section on the line 5a—5a of Fig. 5.

Figs. 6 and 6a are sectional views partly diagrammatic, showing the carriage frame in extended position and the drawer disassembled therefrom.

Referring now to these drawings which illustrate a preferred embodiment of my invention, 1 indicates an enclosing casing of an index cabinet within which a carriage member 2 is slidably mounted to move horizontally back and forth into and out of the casing, and 2' indicates a drawer separably or demountably mounted in said carriage 2 and adapted to have vertical movement relatively to said carriage and cabinet, and provided with rows or stacks of cards 2b mounted in compartments 2a formed between partitions 2a'.

3 indicates a dropping element, preferably comprising a bar mounted to extend longitudinally in the casing and preferably mounted along the median line of the said casing and having a card-supporting portion 3x elevated from the bottom of the cabinet and extending beneath the cards in the drawer. The said dropping element or bar 3 is preferably mounted to have a limited sliding movement longitudinally in the casing, and as shown, has at its front end a yoke 3' sliding beneath struck up lugs 3a (see Fig. 3) and the rear end said bar or element 3 has stretched between a lug 3b thereon and a fixed pin 3c on casing 1 a spring 3d which normally forces the element forward when the drawer is opened, closing of the drawer being adapted to expand or stretch the spring 3d. The lugs 3a and yoke 3' limit the forward movement of the element 3, so that its outer dropping edge extends a short distance outside the casing in front thereof to permit the card-dropping operation to take place outside the cabinet for visibility purposes.

The carriage 2 and the drawer 2' are preferably open at the bottom, are provided with openings or slots 2c, 2c' at such bottoms and the dropping element 3 is mounted on the bottom of the cabinet and extends longitudinally through such bottom openings or slots, the rear partition or wall and the intermediate partitions 2a' being each provided with a vertical opening or slot 2x. The cards 2b are mounted in each compartment or drawer so as normally to extend to the bottom thereof, below the top of the slots 2x.

In the present embodiment of my invention, the mechanism for raising and lowering the card drawer in the frame consists of two bars on each side of the card drawer which bars are arranged as two crossbars on each side and pivotally con-

nected at their middle part to level the vertical movements of the the card-drawer. The bottom ends of the cross-bars are connected to the frame whereas their free top ends, which ends may or may not be provided with wheel or rollers, are supporting the card drawer in its front and rear ends on both sides so that when the card drawer is pushed down the cross bars are pressed down thereby carrying the card drawer to a lower plane and on an even keel. A practical feature of the invention is to provide the cross bars with springs—one for each set, to keep the cross-bars and thereby the card drawer in raised position, the springs being adjusted to bear the weight of both the card drawer and the cards contained therein so that by giving the drawer a slight push downward, the springs contract and the cross bars carry the drawer to the desired elevation. In combination with the downward movement of the drawer a lock arrangement is mounted at the front end of the card drawer and controlled by a latch operated from the front piece of the card drawer in order to enable the card drawer to be locked in a lowered position, for instance, when a continuous dropping is desired.

The drawer, as shown, is mounted in the carriage 2 in such manner as to have vertical movement only in relation thereto and when the dropping element is mounted in the cabinet as hereinabove described, vertical movement of the drawer will cause an extension or projection of the dropping element into the slots 2x so as to elevate those cards in the drawer which are mounted to the rear of the dropping edge of said dropping element. The drawer 2' thus normally supports the cards in a position above the dropping element and is adapted to raise and lower the same in relation to the carriage 2 and casing 1 and to the dropping element mounted with said casing.

As illustrated, the carriage 2 comprises a longitudinally-extending frame member slidable horizontally back and forth within the cabinet and as shown, the sides of said cabinet being provided with rails 7, 7' within which are fitted 45 slide bars 8 having longitudinal grooves 8a into which rails 8' on the carriage member 2 are adapted to extend, thus providing suitable sliding mechanism for said carriage.

In the preferred embodiment of my invention, the carriage 2 is provided at opposite sides with spring drawer-supporting members for normally supporting the drawer in elevated position. These spring members are arranged to normally support the drawer in elevated position and to permit, by manual pressure, downward movement of the drawer to its lowered position.

As shown, the spring drawer-supporting members comprise duplicate systems of obliquely crossed levers or beams 5, each comprising a 60 forwardly extending lever 5' and a rearwardly extending lever 5a pivotally connected intermediate the ends thereof by the shackle member 5x and have springs 6 associated therewith and preferably connected at their middle portion to 65 said shackle member at 6' and having their ends free and resting against an elbow 2e at the sides of the carriage. One of said levers, and as shown, rearwardly extending lever 5a, is pivoted at 5b to the said elbow 2e of the carriage or frame 70 2 and the other forwardly extending lever 5' is provided at its lower end with a roller 5c bearing and movable between the rails 5d and 5d' on the carriage. The upper free ends of said cross-bars are also provided with rollers 5e, 75

5 and extend to a level horizontal plane so as to permit supporting of the drawer thereon in a level plane. As illustrated, the free ends of the levers and their rollers extend, when the 5 drawer is mounted thereon, between outwardly-projecting top flanges 2f on the upper edge of the drawer and are preferably housed beneath such flanges by the provision of side plates or lugs 2d and 2d'. The drawer is thus at all times 10 supported by the spring in elevated position and is automatically held in such position, it being understood that the strength of the springs 6 and the weight of the drawer with its load thereon are substantially balanced but there is a slight 15 additional strength on the part of the springs to maintain the drawer normally in elevated position, while permitting the same to be lowered by manual pressure without undue effort. When the card drawer is thus pressed down manually, 20 the spring-pressed cross-bars will be depressed and the card drawer will be carried on an even keel to a lower plane in which the bottom of the card-drawer will extend below the top of the card dropping element. It will be understood 25 that the springs, as aforesaid, will be adjusted to bear the weight of both the drawer and the cards contained therein so that by slight manual downward push, the spring-pressed levers and springs will be depressed or extended and the 30 drawer will be carried by the cross-bars to the desired lowered position.

In the preferred embodiment of my invention, I provide the drawer with a latching mechanism preferably comprising a spring-pressed latch member 11 pivoted at 11' and pressed by spring 11a, and adapted upon downward movement of the drawer to engage a cross-bar 11c fixed to carriage 2, so as to enable the card drawer to be locked in its lowered position. The 40 latch is released by a manually-movable member 10 mounted on the rear surface of the front drawer plate 9. As shown, the member 10' is guided in ways 10c and a slot 10a, a pin extending through said slot 10a and provided with 45 a knob or finger piece 10b, which upon manipulation will release the latch by inserting the wedge 10d beneath the upper end thereof.

When the drawer is moved, as aforesaid, from its elevated to its lowered position, the row or 50 body of cards will be broken by the edge of the dropping element and thus cards directly above the edge of the dropping element will be exposed as hereinabove stated.

My invention further provides for a ribbon or 55 belt or drawband of any suitable material which runs along the top part of the dropping element and is fastened to the rear end of the frame at the level of the top of the dropping element and in front is carried on a roller through the 60 surface of the dropping element at a suitable distance from the vertical front edge of said dropping element and at the bottom of the dropping element is carried on another roller to and fastened to the front end of the frame so that the ribbon when 65 the drawer is moved out and in of the casing is given a simultaneous movement so that when the card drawer is in a lowered position and the cards are resting on top of the dropping element, said cards are not as heretofore sliding along the 70 surface of the dropping element, but are carried along the dropping element by the movement of the ribbon or drawband thereby eliminating the friction of the cards sliding along the surface of the dropping element and furthermore maintaining 75 a separated and not compressed position of

the cards at their bottom ends which secures a completely even dropping of the cards all through the card drawer.

In the preferred embodiment of my invention, I provide a belt 4 of flexible material which is fastened at one end 4' to the rear end of the carriage member 2, extends therefrom horizontally above the dropping element to a point adjacent to the dropping edge thereof, and then passes over a pin 4a in said dropping element, thence downwardly at the rear of the edge of the said dropping element, and beneath another pin 4b associated with said dropping element, and thence forwardly to a fastening member or connection 4c at the front end of said carriage.

It will be seen that this belt 4 travels with the carriage above the said supporting portion of the dropping element and thus moves with the carriage and drawer in relation to the cabinet and dropping element. Said belt is thus supported by the dropping element and is interposed between said dropping element and the bottom of the cards so that for cards resting thereon, the normal friction between the bottom thereof and said element is substantially reduced and by virtue of the character of the material, this belt will maintain the cards in properly spaced relationship to each other and will prevent any packing thereof during the outward movement of the drawer and its load of cards in relation to the dropping element.

It will be seen that the cards are separated from the dropping element by this belt and are carried forwardly thereby until they reach the point adjacent to the dropping edge.

Another important development in this invention as compared to the above cited previous patent, is a gear arrangement mounted to the rear end of the card drawer or to the rear end of the horizontally movable frame which gear is 40 mounted on a shaft which runs under the entire length of the drawer to the back of the front piece and to provide means for moving this gear arrangement from a knob mounted on the front piece of the card drawer and thereby effecting 45 the movement of a gear which is mounted in such a manner at the rear of said shaft as to engage—when the card drawer is in a lowered position, a gear rack mounted at the bottom of the casing so that by turning the knob on the front piece 50 the forward movement of the card-drawer during the dropping operation may be completely controlled thereby eliminating the danger of a too fast dropping of the cards.

Another important feature of my present invention comprises the provision of mechanism for controlling the movement of the drawer so as to enable a slower or more gradual movement thereof as well as a more positive and definite movement which will enable cards to be dropped 60 in such successive sequence as may be desired by the operator and for this purpose I mount within the cabinet a rack and engage therewith a pinion associated with the carriage and preferably provide bevel gear mechanism for actuating said rack and pinion to permit a positive mechanical movement of the drawer aforesaid, as distinct from an uncertain unpositive manual movement thereof.

As illustrated, I provide a rack 12 having meshing therewith a pinion 12', and operate this pinion to move along the rack by the provision of a bevel pinion 12a connected with the straight pinion 12' and utilize a bevel pinion 12b meshing with the bevel pinion 12a which is mounted on 75

- a rod or shaft 12c extending to the front of the drawer, whereas, as shown, it has mounted thereon a gear 12d which meshes with the gear 12e connected with a short operating shaft passing through the front drawer plate 9 and provided at its outer end with a knurled knob 12f which upon rotation will enable mechanical back and forth movement of the drawer which in turn will provide successive dropping of the cards.
- 10 Having described my invention, I claim:—
1. A vertical index cabinet embodying, in combination, a stationary casing, a drawer slideable with said casing, a card-dropping element mounted in said casing, extending through the bottom of said drawer above the plane thereof and having a substantially horizontal card-supporting surface disposed in an elevated position, and a card dropping edge extending downwardly at substantially right angles to said elevated card-supporting surface, index cards mounted within said drawer, mechanism for raising and lowering the bottom of said cards above and below the top of said dropping element, and mechanical means for controlling the horizontal sliding movement of said drawer within the casing.
- 15 2. A vertical index cabinet embodying, in combination, a stationary casing, a drawer slideable within said casing, a card-dropping element mounted in the bottom of said casing, extending through the bottom of said drawer above the plane thereof, and having a substantially horizontal card-supporting surface disposed in an elevated position, and a card dropping edge extending downwardly at substantially right angles to said elevated card-supporting surface, index cards mounted within said drawer, mechanism for raising and lowering the bottom of said cards above and below the top of said dropping element, and mechanical means for controlling the horizontal sliding movement of said drawer within the casing.
- 20 3. A vertical index cabinet embodying, in combination, a stationary casing, a drawer slideable within said casing, a card-dropping element mounted in the bottom of said casing, extending through the bottom of said drawer above the plane thereof, and having a substantially horizontal card-supporting surface disposed in an elevated position, and a card dropping edge extending downwardly at substantially right angles to said elevated card-supporting surface, index cards mounted within said drawer, mechanism for raising and lowering the bottom of said cards above and below the top of said dropping element, and gear mechanism for controlling the horizontal sliding movement of said drawer within the casing comprising a rack in said casing and a pinion on the drawer meshing with said rack.
- 25 4. A vertical index cabinet embodying, in combination, a stationary casing, a drawer slideable within said casing, a card-dropping element mounted in the bottom of said casing, extending through the bottom of the drawer above the plane thereof, and

having a substantially horizontal card-supporting surface disposed in an elevated position, and a card dropping edge extending downwardly at substantially right angles to said elevated card-supporting surface, a belt mounted within said drawer, above said card-dropping element to extend between the same and the bottom of the cards, and means for raising and lowering the bottom of said cards above and below the plane of the card-supporting surface of said dropping element.

10 5. A vertical index cabinet embodying, in combination, a stationary casing, a card-dropping element mounted in the bottom of said casing, and having a substantially horizontal card-supporting surface disposed in an elevated position, and a card dropping edge extending downwardly at substantially right angles to said elevated card supporting surface, and mechanism for raising and lowering said cards above and below the plane of said card-supporting surface of said dropping element, comprising a carriage-frame movable horizontally back and forth within the casing, a drawer separable from the carriage frame and spring operated supporting mechanism on said carriage frame for normally moving said drawer into elevated position.

15 6. A vertical index cabinet embodying, in combination, a stationary casing, a card-dropping element mounted in the bottom of said casing, and having a substantially horizontal card supporting surface disposed in an elevated position and a card-dropping edge extending downwardly at substantially right angles to said elevated card-supporting surface, and mechanism for raising and lowering said cards above and below the plane of said dropping element, comprising a carriage frame movable horizontally back and forth within the casing, a drawer separable from the carriage-frame and spring-pressed supporting mechanism on said carriage frame for normally moving said drawer into elevated position, and latching mechanism for retaining said drawer in lowered position upon manual movement thereof against the action of said spring-pressed supporting mechanism.

20 30 35 40 45 45 BIRGER AAGAARD.
